Primary Examiner — Cynthia Underwood(74) *Attorney, Agent, or Firm* — Dennemeyer & Assoc.(57) **CLAIM**

The ornamental design for a cover/case for a tablet reader, as shown and described.

DESCRIPTION

FIG. 1 is a front, left and bottom view of the cover/case for a tablet or E-Reader;

FIG. 2 is a rear, right and bottom view of the cover/case for a tablet or E-Reader;

FIG. 3 is a right side view of the cover/case for a tablet or E-Reader;

FIG. 4 is a left side view of the cover/case for a tablet or E-Reader;

FIG. 5 is a top view of the cover/case for a tablet or E-Reader;

FIG. 6 is a bottom view of the cover/case for a tablet or E-Reader;

FIG. 7 is a front side view of the cover/case for a tablet or E-Reader;

FIG. 8 is a rear side view of the cover/case for a tablet or E-Reader;

FIG. 9 is a perspective view of the cover/case for a tablet or E-Reader in an open configuration; and,

FIG. 10 is a perspective view of the cover/case for a tablet or E-Reader in an open and alternative configuration.

The broken line showing depicts environmental subject matter only and forms no part of the claimed design.
